CLAIM

The ornamental design for a digital timer, as shown and described.

DESCRIPTION

FIG. 1 is a perspective view of a digital timer according to my new design.

FIG. 2 is a front view of the digital timer of FIG. 1.

FIG. 3 is a rear view of the digital timer of FIG. 1.

FIG. 4 is a top view of the digital timer of FIG. 1.

FIG. 5 is a bottom view of the digital timer of FIG. 1.

FIG. 6 is a left side view of the digital timer of FIG. 1; and, FIG. 7 is a right side view of the digital timer of FIG. 1.

The portions of the drawings appearing in broken lines are for environment only and do not form a part of the claimed design.
